(57) **CLAIM**

The ornamental design for a guide for plasma cutters, as shown and described.

DESCRIPTION

FIG. 1 is a top perspective view of a guide for plasma cutters, showing my new design;

FIG. 2 is a bottom perspective view thereof;

FIG. 3 is a top plan view thereof;

FIG. 4 is a left elevational view thereof;

FIG. 5 is a right elevational view thereof;

FIG. 6 is a rear elevational view thereof;

FIG. 7 is a front elevational view thereof;

FIG. 8 is a bottom plan view thereof;

FIG. 9 is a top perspective view thereof, shown in an alternate configuration of use;

FIG. 10 is a top front perspective view thereof, shown in an environment of use; and,

FIG. 11 is a top front perspective view thereof, shown in an alternate environment of use.

The broken lines in the figures depict portions of the article and environmental structure which form no part of the claimed design.
